TREATMENT OF HYDROCARBON OILS

Lev A. Mekler, Chicago, Ill., assignor to Universal
Oil Products Company, Chicago, Ill., a corpora-
tion of South Dakota

Application November 22, 1930, Serial No. 497,559
Renewed March 5, 1935

2 Claims. (Cl. 196—48)

This invention relates to the cracking of hydro-carbon oils and refers particularly to the conversion of relatively heavy hydrocarbons into lighter and more valuable products.

5 The invention contemplates the provision of a process and apparatus in which raw oil charging stock, together with the heavier portion of the reflux condensate condensed from the cracked vapors of the process during fractionation, is subjected to relatively mild conversion conditions or what is commonly termed liquid-vapor-phase cracking, while the lighter portions of the reflux condensate, condensed from the cracked vapors of the system during fractionation, are subjected to 10 more severe conversion conditions preferably of the order commonly termed vapor-phase-cracking.

In a specific embodiment of the invention vapors from the relatively high temperature or vapor-phase heating element are combined with heated materials from the relatively low temperature or liquid-vapor-phase heating element, the combined materials pass to an enlarged reaction zone total products from which are withdrawn to 15 a secondary enlarged zone preferably maintained under reduced pressure, vapors and unvaporized material are separated in the secondary enlarged zone, vapors from which are subjected to fractionation, the relatively light and the relatively 20 heavy portions of the insufficiently converted vapors are separately condensed in the fractionating zone, the heavier portions passing together with raw oil charging stock to the relatively low temperature or liquid-vapor-phase heating element, 25 while the lighter portions are subjected to re-vaporization and the vapors resulting therefrom are subjected to reconversion in the relatively high temperature of vapor-phase heating element.

As a feature of the present invention the relatively light reflux condensate from the fractionating zone, which is to be subjected to relatively high temperature or vapor-phase reconversion, is pre-heated by and utilized as a cooling medium for products from the primary reaction zone by indirect contact with said products during their 30 passage from the primary reaction zone to the secondary chamber.

Another feature of the invention provides for further cooling the products withdrawn from the primary reaction zone by recirculating a portion of the cooled unvaporized residual oil from the secondary chamber into the stream of products passing from the primary reaction zone to said secondary chamber.

55 The attached diagrammatic drawing illustrates

one specific form of apparatus embodying the features of the present invention and the following description of the drawing embraces also a description of the process of the invention as it may be practiced in the apparatus shown.

Raw oil charging stock supplied through line 1 and valve 2 to pump 3 is fed through line 4 and may pass through valve 5 into heat exchanger 6, where it is preheated by indirect contact with fractionated vapors, passing therefrom 10 through line 7 and valve 8 from which it may pass through line 9 and valve 10 into preheating coil 11, located in fractionator 12, where it is further preheated by indirect contact with the relatively hot ascending vapors in this zone, passing there- 15 from through line 13 and valve 14 back into line 7. A portion or all of the raw oil may by-pass heat exchanger 6 through line 15 controlled by valve 16. Likewise a portion or all of the raw oil may by-pass preheating coil 11 by passing di- 20 rectly through valve 17, in line 7. Raw oil from line 7 may pass all or in part through line 18 and valve 19 into fractionator 12, preferably at a point below partition 20, where it is further pre-heated by direct contact with the hot ascending 25 vapors in the lower portion of the fractionating zone, assisting their fractionation and passing together with their heavier condensed portion through line 21 and valve 22 into pump 23. From pump 23 the combined materials are fed through 30 valve 25 into line 24, combining therein with that portion, if any, of the raw oil charging stock which may be passed through valve 26, in line 7, into pump 27 and thence through line 28 and valve 29 into line 24.

Heating element 30 is located in any suitable form of furnace 31 and the oil supplied thereto through line 24 is subjected to the desired conversion conditions, preferably within the range of liquid-vapor-phase cracking, and passes there- 40 from through line 32, valve 33, line 34 and valve 35 into reaction chamber 36.

Reaction chamber 36 may be maintained under substantially the same or under reduced pressure relative to that employed in heating element 45 30 and the total products from this zone including liquid and vapor are withdrawn through line 37, valve 38, heat exchanger 39, line 40 and valve 41 to chamber 42.

Chamber 42 may be maintained under substan- 50 tially the same pressure or under reduced pressure relative to that employed in chamber 36 but is preferably, in all cases, maintained under a lower pressure than that employed in heating element 30. Separation of vapors and unvaporized ma- 55

terial is permitted in chamber 42, the unvaporized liquid is withdrawn through line 43 and valve 44, subjected to cooling in cooler 45 thereafter passing through line 46 and valve 47 to pump 48 from which it may be withdrawn all or in part from the system through line 49 and valve 50 or may be recirculated in any desired proportion through line 51 and valve 52 into line 40 combining therein with the relatively hot products from chamber 36 and cooling them to the desired degree. Vapors from chamber 42 pass through line 81 and valve 82 into the lower portion of fractionator 12.

Fractionator 12, as here illustrated, is a single column which may be provided with any suitable fractionating means such as packing, bubble trays, perforated pans or the like, not shown, and is divided into two separate fractionating zones by partition 20. It will be understood that the two separate fractionating zones may employ separate columns, if so desired. Vapors introduced into fractionator 12 from chamber 42 are first subjected to fractionation in the lower portion of the fractionator below partition 20 and that portion of the heavy insufficiently converted vapors condensed in the lower portion of the fractionator passes together with the raw oil charging stock to heating element 30, as already described. The vapors remaining uncondensed in the lower portion of the fractionator pass through partition 20 into the upper portion where they are subjected to further fractionation. Liquid, resulting from condensation in this zone, which is of lighter composition than the reflux condensate withdrawn from the lower portion of the fractionator, collects above partition 20 and is withdrawn through line 53 and valve 54 to pump 55 being thus fed through line 56, heat exchanger 39 and line 57 to heating element 58.

Heat exchanger 39 serves to cool products withdrawn from reaction chamber 36 and reheat the condensate withdrawn from the upper portion of fractionator 12. This reheated condensate is subjected to temperatures in heating element 58 sufficient to effect its substantial vaporization and passes through line 59 and valve 60 into chamber 61. Any unvaporized material may be withdrawn from chamber 61 and from the system through line 62 and valve 63. Any portion or all of this unvaporized material may be diverted from line 62 through line 83 and valve 84 to pump 85 and thence fed through line 86 and valve 87 into line 82 and into the lower portion of fractionator 12. Vapors withdrawn from chamber 61 through line 64 and valve 65, are subjected to reconversion in heating element 66 under any desired conversion conditions, preferably within the range of vapor-phase cracking, and pass through line 67 and valve 68 into line 34, combining therein with heated materials from heating element 30 and passing therewith through valve 35 to reaction chamber 36.

Heating elements 30, 58 and 66 are shown in one furnace structure 31 although it will be understood that separate furnace structures may be employed for each or any of the heating elements and in any case the arrangement of the heating elements is such that the temperature conditions in each may be independently controlled.

Fractionated vapors from fractionator 12, which are preferably within the boiling range or contain a substantial proportion of material boiling within the range of motor fuel, are withdrawn through line 69, valve 70, heat exchanger 6, line 71 and valve 72, are subjected to condensation and cooling in condenser 73 products from which

pass through line 74 and valve 75 to be collected in receiver 76. Distillate may be withdrawn from receiver 76 through line 77 and valve 78. Uncondensable gas may be released through line 79 controlled by valve 80. A portion of the condensed distillate from receiver 76 may, if desired, be recirculated by well known means, not shown, to fractionator 12 to assist fractionation of the vapors in this zone.

Pressures employed within the system may range from subatmospheric to super-atmospheric pressures as high as 1500 pounds or more per square inch. Substantially equalized pressure may be employed throughout the system or differential pressures may be employed between the various elements. Preferably chamber 42 and subsequent portions of the system, namely, fractionator 12, condenser 73 and receiver 76 are maintained under substantially reduced pressure relative to that employed in heating element 30. Conversion temperatures employed may range from 750 to 1200° F., more or less. Preferably more severe conversion conditions are employed in heating element 66 than in heating element 30 while heating element 58 may be operated at relatively mild conversion temperatures or preferably at temperatures below the cracking range.

As a specific example of operating conditions which may be employed and results which may be obtained from the operation, a mid-continent topped crude oil of about 30° A. P. I. gravity is the charging stock for the system and is subjected, together with relatively heavy reflux condensate, to a temperature of about 900° F. under a super-atmospheric pressure of about 275 pounds per square inch. The lighter reflux condensate is substantially revaporized and the vapors are subjected to reconversion at a temperature of about 1000° F. under a pressure of about 100 pounds per square inch. The primary reaction zone is maintained under a substantially equalized pressure of approximately 100 pounds per square inch, and the products withdrawn therefrom to the secondary chamber are cooled to a temperature of about 800° F. by indirect contact with the relatively light reflux condensate and by recirculation of unvaporized residual oil from the secondary chamber. The secondary chamber, the fractionator and the condensing and collecting equipment are maintained under a substantially equalized pressure of about 30 pounds per square inch. An operation such as outlined may yield about 60% of motor fuel having an anti-knock value equivalent to a blend of about 60% benzol and about 40% Pennsylvania straight run gaso-line and in addition a yield of about 23% of fuel oil as the residual product from the system.

What is claimed is:

1. A hydrocarbon oil cracking process which comprises introducing vapors, formed as herein-after set forth, to a fractionating zone and fractionating the same therein in contact with charging oil for the process thereby forming a mixture of charging oil and primary reflux, further fractionating the vapors out of contact with the charging oil to form a relatively light secondary reflux, passing said mixture through a heating zone and heating the same therein to cracking temperature under sufficient pressure to maintain a substantial portion thereof in liquid phase, simultaneously vaporizing a substantial portion of said secondary reflux and heating the resultant vapors independently of and to a higher cracking temperature than said mixture, introducing the thus heated vapors and the heated

5 mixture into an enlarged reaction zone maintained under cracking conditions of temperature and pressure, removing the vaporous and liquid conversion products as a mixture from the reaction zone and lowering the pressure thereon, separating the conversion products into vapors and residue under the reduced pressure, supplying to vaporous conversion products to the fractionating zone as the first-mentioned vapors, and

10 finally condensing the fractionated vapors.

15 2. A hydrocarbon oil cracking process which comprises introducing vapors, formed as herein-after set forth, to a fractionating zone and fractionating the same therein in contact with charging oil for the process thereby forming a mixture of charging oil and primary reflux, further fractionating the vapors out of contact with the charging oil to form a relatively light secondary reflux, passing said mixture through a heating

20 zone and heating the same therein to cracking temperature under sufficient pressure to maintain

a, substantial portion thereof in liquid phase simultaneously vaporizing a substantial portion of said secondary reflux and heating the resultant vapors independently of and to a higher cracking temperature than said mixture, passing the heated mixture from said heating zone through a reaction zone maintained under cracking conditions of temperature and pressure and discharging resultant vapors and liquid conversion products as a mixture into a separating zone main- 5 tained under lower pressure than the reaction zone, also introducing to the separating zone the vaporous conversion products formed by the independent heating of the vapors of said secondary reflux, separating the commingled vaporous conversion products from residue in the separating zone and supplying the former to the fractionating zone as the first-mentioned vapors, and finally condensing the fractionated vapors.
